Patented May 3, 1921.

FIG. I.

FIG. II.

FIG. I.

Inventor
Truman W. Post

By *Chester H. Braselton*
Attorney

UNITED STATES PATENT OFFICE.

TRUMAN W. POST, OF PROVIDENCE, RHODE ISLAND, ASSIGNOR TO WILLYS CORPORATION, OF TOLEDO, OHIO, A CORPORATION OF DELAWARE.

HEADLIGHT.

1,376,576.

Specification of Letters Patent.

Patented May 3, 1921.

Application filed September 12, 1917. Serial No. 190,976.

To all whom it may concern:

Be it known that I, TRUMAN W. Post, a citizen of the United States, residing at Providence, in the county of Providence and State of Rhode Island, have invented 5 certain new and useful Improvements in Headlights, of which I declare the following to be a full, clear, and exact description.

This invention relates to improvements in 10 headlights and more particularly to headlights of the tilting reflector type, in which the reflector is pivotally mounted within the headlight casing so that it may be tilted to a position in which the beam of light is deflected downwardly upon the ground in 15 order to eliminate the glare.

The principal object of my invention is 20 to provide, in a tilting reflector headlight, improved means for carrying the electric light bulb socket and for adjusting said 25 socket for the purpose of focusing, together with means rendering the focusing means readily accessible from the rear of the headlight casing.

25 Further objects of this invention relate to economies of manufacture and details of construction as will hereinafter appear from the detailed description to follow. I accomplish the objects of my invention in one 30 instance by the devices and means described in the following specification, but it is evident that the same may be varied widely without departing from the scope of the invention as pointed out in the appended 35 claims. A structure constituting one embodiment of my invention, which may be the preferred, is illustrated in the accompanying drawings forming a part hereof in which:

40 Figure I is a vertical, sectional view, taken through a headlight embodying my invention.

Fig. II is an enlarged, fragmentary, detail view, showing in vertical section the 45 means for carrying the electric light bulb socket on the reflector.

Fig. III is a fragmentary, elevational view of the rear end of the headlight casing.

In the drawings, similar reference numerals 50 refer to similar parts throughout the several views.

Considering the numbered parts of the drawing, my invention comprises a headlight casing 10, the forward end of which 55 is closed by a lens 11 carried by a ring 12

secured to the front edge of the headlight casing. The usual parabolic reflector 13 is mounted within the casing 10 and carries a rearwardly extending sleeve 14, in which the socket 22 of the light bulb 15 is mounted. 60 The forward edge 16 of the reflector is rolled back around a wire 17 to form a reinforcing bead for the front of the reflector and said bead carries trunnions 18 which are diametrically opposite and extend in a horizontal plane, forming the horizontal axis upon which the reflector is pivotally mounted. A connector 19 is carried by the casing 10 and the socket 22 of the electric light bulb 15 is connected with said connector by 65 the wires 20 which pass through the slot 21 formed in the sleeve 14. The bulb 15 is connected with the socket 22 by the usual bayonet slot joint. A cap 23 is secured on the rear end of the sleeve 14 and a stud 24 is 70 rotatably mounted in said cap 23 and cooperates with a screw 25 which extends from the rear end of the socket 22. An opening 26 is formed in the rear end of the casing 10 in line with the sleeve 14 and said opening is closed by the disk 27 which is pivoted 75 on pin 28, as shown in Figs. I and III. A clamp ring 29 embraces the sleeve 14 and is connected to the operating mechanism by a wire 30, which passes out through a sleeve 80 32 carried by boss 31 secured to the casing 10, said tube being held in adjusted position by means of the set screw 33. A nub 34 is struck up from the casing 10 adjacent the opening 26 and is adapted to engage a corresponding depression 35 formed in the disk 27. A slot 36 is provided in the sleeve 14 and a lug 37 on socket 22 projects into said slot so as to prevent the socket from turning 85 in said sleeve.

95 The electric light bulb and socket are entirely carried by the reflector 13 and the flexible connections 20 permit of the tilting of the reflector relative to the casing 10. The socket 22 is adjustable longitudinally 100 of the sleeve 14, in order to properly position the bulb 15 and the light source, for the purposes of focusing, said adjustment being effected by turning the stud 24 threaded on the screw 25. The disk 27 closing the opening 26 may be moved to one side so that a screw driver may be inserted through the opening 26 by means of which the stud 24 may be rotated in order to effect this adjustment. I have shown a mechanical arrangement. 105 110

ment for tilting the headlight, but this is merely illustrative, as my invention is not concerned with the means for tilting the reflector within the casing. In the embodiment shown, the reflector is tilted by a pull on the wire 30 which is connected to the clamp ring 29.

I am aware that the particular embodiment of my invention, here shown and described, is susceptible of considerable variation without departing from the spirit thereof and therefore I desire to claim my invention broadly as well as specifically, as indicated by the appended claims.

Having thus described my invention, what I claim as new and desire to secure by Letters Patent, is:

1. In a headlight, the combination of a casing, a reflector tiltably mounted therein, a sleeve secured to said reflector, a lamp socket slidable longitudinally in said sleeve, lamp adjusting means comprising co-operative parts respectively carried by the rear end of said sleeve and said socket to slide the latter and means for tilting said reflector, said means being secured to said sleeve intermediate the reflector and the adjusting means, and said casing being provided with an opening at the rear for the insertion of a tool to operate the adjusting means.

2. In a headlight, the combination of a casing, a reflector tiltably mounted therein, a sleeve secured at one end to said reflector,

a lamp socket slidably longitudinally in said sleeve, a cap secured to the other end of said sleeve, screw threaded means operatively engaging said cap and said socket for sliding the latter and means for tilting said reflector comprising a rod extending through said casing and a coöperating member connected with said sleeve in the space between the reflector and the cap, said casing being provided at its rear with an opening for the insertion of a tool to operate said screw threaded means.

3. In a headlight, the combination of a casing, a reflector tiltably mounted therein, a sleeve secured at its forward end to said reflector, a lamp socket mounted for longitudinal movement in said sleeve, a cap secured to the rear end of said sleeve, a screw carried by and extending rearwardly of said socket, a nut for said screw mounted in said cap and having means permitting rotative movement but preventing longitudinal movement, tilting means for said reflector comprising a band surrounding said sleeve intermediate said reflector and said cap and a rod secured thereto and passing through said casing and a conductor connected with said socket and passing through the side of said sleeve intermediate said reflector and said cap, said casing having an opening for the insertion of a tool to operate said nut.

In testimony whereof I affix my signature.

TRUMAN W. POST.
